UNITED STATES PATENT OFFICE.

EDWARD E. RITTER, OF MILTON, PENNSYLVANIA.

NOZZLE.

SPECIFICATION forming part of Letters Patent No. 772,827, dated October 18, 1904.

Application filed February 2, 1904. Serial No. 191,711. (No model.)

To all whom it may concern:

Be it known that I, EDWARD E. RITTER, a citizen of the United States, residing at Milton, in the county of Northumberland and 5 State of Pennsylvania, have invented a new and useful Nozzle, of which the following is a specification.

This invention relates to nozzles of that class which are largely employed for street 10 sprinkling and cleaning purposes and which may be used in connection with sprinkling apparatus of all kinds.

My invention has special reference to that class of nozzles which are provided with a slit 15 through which water or other liquid is discharged in the form of a sheet; and the object of the present invention is to provide improved means whereby the size of the slit or escape-opening may be conveniently regulated, whereby the range or scope of adjustment may be large, and whereby leakage shall 20 be avoided.

With these and other ends in view the invention consists in the improved construction, 25 arrangement, and combination of parts, which will be hereinafter fully described, and particularly pointed out in the claims.

In the accompanying drawings, Figure 1 is a perspective view of a nozzle constructed in 30 accordance with the principles of my invention. Fig. 2 is a vertical sectional view of the same. Fig. 3 is a sectional view taken at right angles to Fig. 2. Fig. 4 is a sectional view taken on the line 4-4 in Fig. 2.

35 Corresponding parts in the several figures are indicated by similar numerals of reference.

My improved nozzle may be described as comprising a section of pipe 1, closed at one 40 end, as shown at 2, and screw-threaded at its opposite end, as shown at 3, for connection with a supply-pipe. The pipe-section or body 1 is provided with a laterally-extending nipple 4, the perforation through which, 5, forms 45 a bearing for a shaft 6, carrying at its inner end a disk 7, which is accommodated in a recess or enlargement 8 at the inner end of the nipple. The outer end of the shaft 6 carries 50 an operating lever or handle 9, between which and the end of the nipple a spring 10 is inter-

posed to force the shaft in an outward direction, and thus to afford frictional contact between the outer side of the disk 7 and the adjacent side of the recess 8, whereby a practically water-tight joint is formed. 55

The pipe-section or body 1 is provided adjacent to the closure 2 with a peripheral slit or opening 11, which may be of any desired length and width to admit of the passage of the maximum quantity of fluid which it may 60 be desired at any time to discharge. Internally of the body or pipe-section 1 is disposed a slidable sleeve 12, composed of an elastic band of spring-steel or other suitable material, which is bent to cylindrical shape, so as to fit 65 in the pipe-section or body 1, within which it expands, so as to lie closely in contact with the walls thereof, the ends of the band forming the sleeve being when the latter is expanded slightly spaced apart, as will be seen 70 at 13. This spaced portion is preferably disposed diametrically opposite to the slit or opening 11, and to the said sleeve is secured a flange 14, which is movable in the slit 11 and which limits the movement of the sleeve 75 12. This flange 14 is adapted to abut upon the edge of the slit 11 adjacent to the closure 2 in such a manner as to form a practically water-tight closure.

In the wall of the sleeve 12 is formed an L-shaped slot or notch 15, which is engaged by a pin 16, which extends from the disk 7 at the inner end of the shaft 6. It will thus be seen that by partially rotating the shaft 6, by means of the lever or handle 9, the sleeve 12 may be 80 adjusted longitudinally within the pipe-section or body 1, thereby uncovering to any desired extent the slit or opening 11, and thus forming an escape-passage the width of which is capable of being adjusted with great nicety. 85 90

From the foregoing description, taken in connection with the drawings hereto annexed, the operation and advantages of my invention will be readily understood. The device is capable of being manufactured at a comparatively trifling expense, and it may be readily connected with any suitable source of supply—such as, for instance, a tank for street-sprinkling purposes supported upon wheels. The improved nozzle which forms the subject 100

of my invention may be used in any position—that is, the pipe-section which constitutes the main body thereof may be placed either in a vertical or in a horizontal position, so that 5 the discharge through the slit 11 shall be properly directed. The operating lever or handle 9 may be connected in any suitable manner with operating means located at a distance from the nozzle, so that adjustment of the size 10 of the discharge-opening or the closure of the latter may be conveniently effected at any time. The elastic nature of the expansion-sleeve 12 enables leakage to be avoided, and it is obvious that wear upon the said sleeve 15 and upon the interior surface of the pipe-section forming the body of the device will be constantly and automatically compensated for.

I desire it to be understood that while I have in the foregoing described a simple and 20 preferred form of my invention I do not necessarily limit myself to the precise structural details herein shown and described, but reserve a right to such changes and modifications as lie properly within the scope of my 25 invention and which may be resorted to without departing from the spirit or sacrificing the utility of the same.

Having thus described my invention, I claim—

- 30 1. In a device of the class described, a cylindrical body having a closure at one end, a slit adjacent to said closure, and an interiorly-disposed longitudinally-movable sleeve having a flange movable in said slit.
- 35 2. In a device of the class described, a cylindrical body having a closure at one end and a slit adjacent to said closure, an interiorly-disposed longitudinally-movable and laterally-expansible sleeve, and a flange upon said 40 sleeve engaging the slit in the cylindrical body.
- 45 3. In a device of the class described, a cylindrical body having a closure at one end and

a slit adjacent to said closure, an expansible sleeve longitudinally movable in said body 45 and having a flange engaging the slit, and means for effecting the longitudinal adjustment of said sleeve to form a partial or complete closure for the slit.

4. In a device of the class described, a cy- 50 lindrical body having a laterally-extending nipple and provided with a closure at one end and with a slit adjacent to said closure, a longitudinally-movable, expansible sleeve within said body adapted to form a closure for the 55 slit therein, and a shaft journaled in the nipple and having engagement with the sleeve whereby the latter may move longitudinally within the cylindrical body.

5. In a device of the class described, a cy- 60 lindrical body having a closure at one end, a slit adjacent to said closure and a laterally-extending nipple, a sleeve slideable within said body and adapted to form a closure for the slit, said sleeve being provided with an L- 65 shaped slot, and a shaft journaled in the nipple and having a pin engaging said slot.

6. In a device of the class described, a cy- 70 lindrical body having a closure at one end and a slit, a sleeve longitudinally slideable in said body and adapted to form a closure for the slit, a nipple extending laterally from the body and having a bore enlarged at its end, a shaft journaled in said nipple and having a disk engaging the enlarged portion of the bore, 75 a pin extending from said disk and engaging a slot in the slideable sleeve, a handle upon the shaft, and spring means to force the latter in an outward direction.

In testimony that I claim the foregoing as 80 my own I have hereto affixed my signature in the presence of two witnesses.

EDWARD E. RITTER.
